UNITED STATES PATENT OFFICE.

DAVID MORE, OF OMAHA, NEBRASKA.

PISTON-VALVE.

1,358,569.

Specification of Letters Patent.

Patented Nov. 9, 1920.

Application filed February 12, 1919. Serial No. 276,587.

To all whom it may concern:

Be it known that I, DAVID MORE, a citizen of the United States, residing at Omaha, in the county of Douglas and State of Nebraska, have invented new and useful Improvements in Piston-Valves, of which the following is a specification.

This invention relates to piston valves such as are commonly employed in locomotive steam engines. The object of the invention is to provide a novel arrangement of packing rings on the follower heads of the piston valve body, whereby one of the packing rings is permitted to have a limited lateral movement or a movement to a limited extent longitudinally of the valve body, means in the form of an additional packing ring being employed to protect the said laterally movable ring by preventing the steam pressure from acting thereon at certain points in the movement of the piston valve.

By means of the improved construction hereinafter described and illustrated in the accompanying drawings, is a short cut off which steam port is uncovered for a longer period of time with a corresponding reduction of compression and a proportionate increase in the expansive use of the steam. Also during the exhaust position of the valve, the port is left uncovered for a greater period of time thus relieving compression, and a free and less opposed movement of the piston is obtained.

With the above and other objects in view, the invention consists in the novel construction, combination and arrangement of parts, herein described, and claimed.

In the accompanying drawings hereby made a part hereof;

Figure 1 is a diametrical section showing the application of my novel valve.

Fig. 2 is an enlarged detail of a portion of the packing.

Referring to the drawings 1 designates the valve chest or casing containing bushing 2 in which reciprocates the piston valve designated generally at A, 3 designating the steam ports, 4 the steam inlet chamber and 5 the exhaust chambers. The valve is

mainly of the ordinary well known construction embodying the thimble or main body portion 6 and the heads 7 at the opposite ends thereof, the heads being held in fixed relation to the body 6 by means of the valve stem 8 having a shoulder 9 and a nut 10 between which the heads 7 are clamped.

Each head 7 is rabbeted as shown to receive the usual bull ring 11 and said bull ring is in turn rabbeted to receive the split packing rings 12 and 13. Up to this point the construction hereinabove described corresponds with the present day standard piston valve as used in locomotive steam engines.

In carrying out the present invention, I make the groove 14 in which the packing ring 13 is placed, of greater width than that portion of the ring which lies therein so that the ring is adapted to move laterally in the groove 14 or longitudinally with respect to the length of the piston valve as a whole. Each packing ring 13 has a floating movement for the purpose of gaining a longer expansive use of the steam on the release movement of the valve, and a longer opening on the closing movement of the valve. When the valve is moved in either direction, the rings 13 are moved by the valve, the frictional contact between the rings 13 and the bushing 2 having a tendency to hold the rings on the return movement in either direction. The rings 13 are of less width than the grooves in which they are arranged, and hence the said rings are able to float from one side of the groove to the other on movement of the valve to function as described—i. e., to hold steam a longer time in the cylinder on the opening movement of the valve, and to hold the ports open longer to allow compression to start, on the closing movement of the valve.

At 15 are intermediate rings. Each ring 15 serves to protect the packing ring 13 adjacent thereto from live steam, the adjacent ring 12 being of a less width than the port 3. Thus when the valve begins to open, if the ring 15 were not employed, steam would pass under the ring 12 around to the back side and would push the ring 13 to the outer

edge of the groove. Such action, however, is effectively prevented by the employment of the ring 15.

I claim:—

5 A piston valve having a groove and a packing ring mounted in the groove, said groove being of greater width than that portion of the ring which lies therein, whereby said ring is adapted to shift laterally in the

back and forth movements of the piston 10 valve, in combination with an auxiliary packing ring back of and spaced from the first-named ring, and a third ring intermediate of the first and second rings to protect the first ring from live steam.

15

In testimony whereof I affix my signature.

DAVID MORE.
